RETAINING DEVICE

Irving Steinhardt, New York, N. Y.

Application November 4, 1941, Serial No. 417,749

13 Claims. (Cl. 70—456)

This invention relates to retaining devices and more particularly to devices intended for use as key rings or the like and also adapted to numerous other uses.

One object of the invention is to provide a device of the class described formed of parts which can be easily assembled and held in assembled relation by the interengagement of the parts, separate fastening means for holding the parts in assembled relation being unnecessary.

Another object of the invention is to provide a device of the class described which can be used in various ways and which by reason of its construction is also ornamental.

The above and other objects, features and advantages of the invention will be explained more in detail in the following description considered in connection with the accompanying illustrative drawings.

In the drawings:

Fig. 1 is a side view of a device embodying the present invention;

Fig. 2 is a side view of the device showing the parts in open position;

Fig. 2A is a side view showing the manner of assembling the device;

Figs. 3 and 4 are top and bottom views, respectively, of one of the parts;

Fig. 5 is an enlarged sectional view on the line 5—5 of Fig. 3;

Fig. 6 is a side view of one end portion of one of the parts;

Fig. 6A is a side view of the other end portion of one of the parts;

Figs. 7 and 7A are views of said end portions, respectively, as viewed along the lines 7—7 and 7A—7A, respectively, of Figs. 6 and 6A;

Fig. 8 is a sectional view of a locking member and one of the end portions of one of the parts of the device;

Fig. 9 is a detail sectional view on the line 9—9 of Fig. 8;

Figs. 10, 11 and 12 are views similar to Figs. 5, 6 and 7 illustrating a modification of the invention, the view of Fig. 12 being taken along the line 12—12 of Fig. 11.

Referring now to the drawings in detail, the device embodying the present invention is illustrated in a form intended for use as a key ring and comprises, as here shown, parts 10 and 12 which for convenience in reference may be designated as looped and yoke members, respectively. Said members 10 and 12 can be formed of any suitable material; for example, metal, plastic, wood, etc. and it will be understood that both

members can be of the same material or one member can be made of one material and the other member can be made of another material. Preferably, said members 10 and 12 are made of a plastic, for example, "Bakelite," or any other suitable plastic of which there are many different types available on the market. As here shown, looped member 10 simulates a horseshoe in appearance and by reason of its shape is resilient, the end portions 14 and 16 of said member being movable toward each other when appropriate pressure is applied to said member, said end portions being automatically movable away from each other when said pressure is released. The end portions 14 and 16 of looped member 10 are received in yoke member 12 and in the position illustrated in Fig. 1 engage said yoke member in openings 18 and 20, respectively. There is here shown an integral cross piece 22 which extends transversely of member 12 substantially centrally thereof between said openings 18 and 20.

The end portions 14 and 16 have out-turned parts 24 and 26 which, in the position of parts 10 and 12 illustrated in Fig. 1, engage the transversely extending wall portions 28 and 30, respectively, formed adjacent the bottom of yoke member 12 internally thereof adjacent openings 18 and 20, respectively. Opening 18 is narrower than opening 20 and is provided with narrow wall portions 32 at opposite sides of opening 18 and continuous with wall portion 28, and the out-turned part 24 of end portion 14 is provided with lateral projections 34 at the opposite sides thereof (Figs. 6 and 7). Each of said projections has an inclined surface 36 which is adapted to engage the adjacent wall portion 32 which as illustrated in Fig. 5 are inclined upwardly toward the top of yoke member 12. When members 10 and 12 are in the relative positions illustrated in Fig. 1 the upper edges 38 and 40 of end portions 14 and 16, respectively, engage wall portions 28 and 30, respectively, thus preventing upward movement of looped member 10 in relation to yoke member 12. When, however, pressure is applied to looped member 10 for moving end portion 16 toward end portion 14 of said member the out-turned end part 26 of said end portion 16 can be moved clear of the inner edge 44 of wall portion 30 thus to permit end portion 16 to be disengaged from yoke 12 and moved upwardly through opening 20 to the position illustrated in Fig. 2. It will be noted that it is not possible to similarly disengage end portion 14 from the yoke member and that, on the contrary, parts

34 and more particularly shoulders 36 thereof engage wall portions 32 in the position of the parts illustrated in Fig. 2, thus limiting the relative movement of looped member 10 and yoke member 12. Thus, it will be observed that end portion 14 provides a pivotal connection between looped member 10 and yoke member 12, said looped member being thus swingably connected to the yoke member.

As illustrated in Figs. 10 to 12, instead of forming end portion 14 of looped member 10 with enlargements 34 of the character described above, said end portion can be formed with nibs 34a and the yoke member indicated at 12a in Fig. 10, which yoke member is otherwise of the same construction as the yoke member 12 described above, is provided with wall portions 32a corresponding to wall portions 32 but of less length than the latter and each having a rounded surface portion 32b formed adjacent to a vertical wall portion 32c. The pivotal action between the looped member having the nibs 34a and the yoke member 12a is substantially the same as described above, except that the limit to the turning movement of the looped member in respect to the yoke member instead of being effected as described above by the engagement of shoulders 36 with wall portions 32 is accomplished by the engagement of the outer edge of the looped member adjacent end portion 14 with the upper surface portion 35 of yoke member 12a.

When members 10 and 12 are in the positions illustrated in Fig. 1 the outer edges of end portions 14 and 16 adjacent out-turned parts 24 and 26 are adjacent to the inner edges 42 and 44, respectively, of openings 18 and 20 and due to the fact that looped member 10 diverges upwardly from said end portions, any substantial movement of said looped member downwardly of yoke member 12 is prevented while upward movement of said looped member is prevented, as stated above, by the engagement of the upper edges 38 and 40 of said end portions with wall portions 28 and 30.

End portion 16 of looped member 10 is not provided with lateral enlargements but is of the same thickness as the body portion of said looped member. More specifically, looped member 10 is preferably of uniform thickness except at the out-turned end portion 24 of end portion 14 which, as described above, is provided with the lateral projections or enlargements 34. Accordingly, while out-turned end portion 24 cannot pass through opening 18, the rest of said looped member can be passed through said opening 18 and further all of said looped member except part 24 can pass through opening 20. The purpose of this construction is to enable parts 10 and 12 to be assembled and arranged in the position illustrated in Fig. 1. The manner of assembling the parts will be clearly understood after it is first explained, by reference to Fig. 2, how looped member 10 can be completely separated from yoke member 12. This is accomplished by moving the end portion 14 downwardly of yoke member 12 and out through the bottom of said yoke member, and to facilitate this, said looped member is flexed laterally and rearwardly (viewing Fig. 2) so that end portion 16 is clear of the side 46 of said yoke member after which continued turning movement of said looped member in a counter-clockwise direction, viewing Fig. 2, brings end portion 16 in registry with and above opening 18, and upon continued movement of looped member 10 in said direction said end portion 16

is moved through and completely separated from said yoke member. In the position of the parts 10 and 12 just prior to their complete separation, looped member 10 is located below yoke member 12, with end portion 16 in opening 18 and end portion 14 in engagement with side 48 of the yoke member adjacent opening 20. This position of the parts 10 and 12 is illustrated in Fig. 2A. It will now be understood that for assembling looped member 10 with yoke member 12 from their completely separated condition end portion 16 is inserted through opening 18 from the bottom of yoke member 12 to bring about the position illustrated in Fig. 2A, after which said looped member is turned in a clockwise direction, viewing Fig. 2A, to the position illustrated in Fig. 2, after which by applying pressure to the looped member end portion 16 can be passed through opening 20 for positioning parts 10 and 12 as illustrated in Fig. 1.

The device as thus far described can, if desired, constitute the complete device, and as thus constituted said device comprises the yoke member 12 and looped member 10 which in the position of said members illustrated in Fig. 1 forms a peripherally continuous structure having an opening 54 therein defined by said members. By disengaging end portion 16 from yoke member 12 while leaving end portion 14 in engagement with said yoke member, as illustrated in Fig. 2, keys or other articles can be engaged on looped member 10 inwardly of end portion 16, said looped member 10 passing through the usual openings in said keys or other articles provided with openings. Thus, as illustrated in Fig. 2 members 10 and 12 are relatively movable to provide an opening in the periphery of the structure forming a passage between end 26 of loop 10 and the adjacent end of yoke 12 into the main opening indicated at 54, which as hereinbefore indicated is defined by the inner edge 58 of looped member 10 and by the upper surface of yoke member 12.

It will be understood that the structure constituted by members 10 and 12 can be used for purposes other than a key ring or other retaining device. For example, a series of structures each constituted by said looped and yoke members can be interlinked to form an ornamental chain or similar device of any desired length, depending upon the number and size of said inter-linked structures. Also, if desired, one of said structures can be attached to a chain and suspended therefrom as an ornament. By way of example of another use, a pin can be attached to member 10 and the device used as an ornamental device or for supporting an ornament from member 12. It will be understood that the uses for the device are not limited to those just described but, on the contrary, said device can be used in various other ways and for various other purposes.

In accordance with the preferred embodiment of the invention as illustrated herein the device hereinbefore described is provided with means for locking members 10 and 12 in the closed relation thereof illustrated in Fig. 1. For this purpose there is provided a locking member 60 which in the position illustrated in Fig. 1 engages looped member 10 at the open end thereof and extends across said open end between end portions 14 and 16 to prevent relative movement of said end portions toward each other thus to prevent disengagement of end portion 16 from yoke member 12. Locking member 60 is provided with

small protuberances 62 at its opposite ends which snap into small companion recesses 64 in end portions 14 and 16 for more securely holding the ends of member 60 in engagement with the end portions 14 and 16 of looped member 10. When locking member 60 is in its locking position, illustrated in Fig. 1, a part 66 thereof of reduced width is received within yoke member 12 and a recess 68 formed in said locking member centrally thereof receives cross piece 22 of said yoke. Said recess 68, in conjunction with the curved formation of said locking member 60 facilitates flexing of said locking member for engaging the opposite ends thereof resiliently with the end portions 14 and 16 of looped member 10. The thicker end portion 70 of member 60 provides finger pieces at both sides of said locking member to facilitate movement thereof to the releasing position illustrated in Fig. 2, and to improve this action said wider portion 70 preferably extends outwardly somewhat beyond the adjacent sides 46 and 48 of yoke member 12.

As illustrated in Fig. 1 the device is provided with means for facilitating handling thereof or for the attachment thereto of ornamental means. In either case whether for the purpose of facilitating handling or for ornamental purposes, said means, in the form here shown, comprises a cord 72 which is looped to locking member 60 for which purpose said locking member is provided with spaced holes 74 therethrough, the ends of said cord 72 being fastened together by a connector 76. As here shown, a ball or other ornamental element 78 is attached to connector 76 by several chain links 80. The upper part of locking member 60 is provided with a groove 82 extending between holes 74 for receiving the looped end 84 of cord 72. It will be understood that when locking member 60 is omitted and when it is desired to use a handle or ornamental means such as that just described, the cord 72 can be attached to the cross piece 22, being looped around said cross piece and passing through the recesses 66 formed, as illustrated in Figs. 3 and 4, as continuations of openings 18 and 20.

While I have shown and described the preferred embodiment of my invention, it will be understood that the latter may be embodied otherwise than as herein shown or described and that in the illustrated embodiment various changes may be made. Therefore I do not wish to be limited to the construction as herein shown or described, except to the extent which may be required by the scope of the appended claims.

Having thus described my invention, what I claim and desire to secure by Letters Patent is:

1. A device of the class described comprising a looped resilient member having spaced end portions movable toward and away from each other, a one-piece yoke member having openings in which said end portions are received, respectively, said yoke member forming with said looped member a peripherally continuous structure defining an opening therein, said end portions of said looped member having out-turned free ends extending away from each other and movably positioned in direct engagement with the opposite ends, respectively, of said yoke member, at least one of said out-turned ends of said looped member being disengageable from said yoke member and movable to a position spaced therefrom, while the other end portion of said out-turned ends of said looped member is engaged with said yoke member, whereby to form an opening in the periphery of the structure for

providing a passage to and from said first mentioned opening, all of said looped member except said other out-turned end being movable through the opening in which said other end portion is received, for assembling and disassembling said looped member and said yoke member.

2. A device of the class described comprising a looped resilient member having spaced end portions movable toward and away from each other, 10 a one-piece yoke member having openings in which said end portions are received, respectively, said yoke member forming with said looped member a peripherally continuous structure defining an opening therein, said end portions of said looped member having out-turned free ends extending away from each other and movably positioned in direct engagement with the opposite ends, respectively, of said yoke member, at least one of said out-turned ends of said 20 looped member being disengageable from said yoke member and movable to a position spaced therefrom, while the other of said out-turned ends of said looped member is engaged with said yoke member, whereby to form an opening in the periphery of the structure for providing a passage to and from said first mentioned opening.

3. A device of the class described comprising a looped resilient member having spaced end portions movable toward and away from each other, 30 a one-piece yoke member having openings in which said end portions are received, respectively, said yoke member forming with said looped member a peripherally continuous structure defining an opening therein, said end portions of said looped member having out-turned free ends extending away from each other and movably positioned in direct engagement with the opposite ends, respectively, of said yoke member, at least one of said out-turned ends of said 35 looped member being disengageable from said yoke member and movable to a position spaced therefrom, while the other of said out-turned ends of said looped member is engaged with said yoke member, whereby to form an opening in the periphery of the structure for providing a passage to and from said first mentioned opening, and interengaging means on said yoke member and said other end portion of the looped member for preventing unintended disengagement of the 40 latter from said yoke member, all of said looped member except said other out-turned end being movable through the openings in said yoke member for assembling and disassembling said looped member and said yoke member.

5. A device of the class described comprising a looped member having relatively movable end portions, and a yoke member having openings in which said end portions are received, respectively, and forming with said looped member a 50 peripherally continuous structure, said openings of said yoke member and said end portions of said looped member being so shaped and related to each other that only one of said end portions can pass through said openings and so that all 55 of said looped member except said one end portion can pass through said openings for assembling said looped member with said yoke member, said one end portion having a part which is larger than either of said openings and is thereby prevented from passing through either of said openings, said other end portion being disengageable from said yoke member to form an opening in the periphery of said structure, said one of the end portions of said looped member having a 60 transverse projection extending in the direction 70 75

between said side portions of the yoke member and engaging the adjacent end of said yoke member to limit movement of said end of the yoke toward the end of said one of the end portions of the looped member.

5. A device of the class described comprising a looped member having relatively movable end portions, and a yoke member having openings in which said end portions are received, respectively, and forming with said looped member a peripherally continuous structure, said openings of said yoke member and said end portions of said looped member being so shaped and related to said openings that only one of said end portions can pass through said openings and so that all of said looped member except said one end portion can pass through said openings for assembling said looped member with said yoke member, said one end portion having a part which is larger than either of said openings and is thereby prevented from passing through either of said openings, said other end portion being disengageable from said yoke member to form an opening in the periphery of said structure, said one of the end portions of said looped member having a transverse projection extending in the direction between said side portions of the yoke member and engaging the adjacent end of said yoke member to limit movement of said end of the yoke toward the end of said one of the end portions of the looped member, said other end portion of the looped member having a resilient releasable engagement with said yoke member in the companion opening of the latter.

6. A device of the class described comprising a looped member having relatively movable end portions, and a yoke member having openings in which said end portions are received, respectively, and forming with said looped member a peripherally continuous structure, said openings of said yoke member and said end portions of said looped member being so shaped and related to said openings that only one of said end portions can pass through said openings and so that all of said looped member except said one end portion can pass through said openings for assembling said looped member with said yoke member, said one end portion having a part which is larger than either of said openings and is thereby prevented from passing through either of said openings, said other end portion being disengageable from said yoke member to form an opening in the periphery of said structure, said one of the end portions of said looped member having a transverse projection extending in the direction between said side portions of the yoke member and engaging the adjacent end of said yoke member to limit movement of said end of the yoke toward the end of said one of the end portions of the looped member, said yoke member having a cross piece between said openings.

7. A device of the class described comprising a looped member having relatively movable end portions, and a yoke member having openings in which said end portions are received, respectively, and forming with said looped member a peripherally continuous structure, said openings of said yoke member and said end portions of said looped member being so shaped and related to each other that only one of said end portions can pass through said openings, said last mentioned end portion being disengageable from said yoke member to form an opening in the periphery of said structure, said yoke member having a cross piece between said openings, a cord

looped around said cross piece, and a locking member attached to said cord and releasably engageable with said end portions for releasably preventing disengagement of said last mentioned end portion from said yoke member.

8. A device of the class described comprising a looped member having relatively movable end portions, and a yoke member having openings in which said end portions are received, respectively, and forming with said looped member a peripherally continuous structure, one of said openings being narrower than the other and one of said end portions being dimensioned to prevent it from passing through said narrower opening, the other of said end portions and the rest of said looped member except said one of the end portions being movable through said narrower opening for assembling said members, said dimensional relationship between said narrower opening and said one of the end portions preventing unintended separation of said members said end portions of said looped member having out-turned free ends extending away from each other and movably positioned in direct engagement with the opposite ends, respectively, of said yoke member.

9. A device of the class described comprising a looped member open at one end thereof and terminating at said open end in spaced relatively movable end portions, and a member engaging said end portions and extending across said open end, said member having recesses in which said end portions, respectively, are received one of said end portions having lateral projections at opposite sides thereof extending in a direction transverse to the line across the open end of said looped member and received in one of said recesses, in said last mentioned member and engaging portions thereof for providing a pivotal engagement therewith, and the other of said end portions having a releasable engagement with said last mentioned member, said yoke member having an opening through which all of said looped member, except said one end portion thereof, is movable in either of two directions for assembling and disassembling said members, said lateral projections limiting the movement of said yoke member in one direction through said opening.

10. A device of the class described comprising a looped member open at one end thereof and terminating at said open end in spaced relatively movable end portions, and a member engaging said end portions and extending across said open end, one of said end portions having lateral projections at opposite sides thereof received in said last mentioned member and engaging portions thereof for providing a pivotal engagement therewith, said projections having inclined surfaces which abut said portions of said last mentioned member for limiting the pivotal movement of said looped member.

11. A device of the class described comprising a looped member open at one end thereof and terminating at said open end in spaced relatively movable end portions, and a member engaging said end portions and extending across said open end, one of said end portions having nibs projecting from opposite sides thereof and said last mentioned member having grooves in which said nibs are received for providing a pivotal engagement with said last mentioned member, and the other of said end portions having a releasable engagement with said last mentioned member, said yoke member having an opening through

which all of said looped member except said one end portion thereof is movable in either of two directions for assembling and disassembling said members, said nibs limiting the movement of said yoke member in one direction through said opening.

12. A device of the class described comprising a looped member open at one end thereof and terminating at said open end in spaced relatively movable end portions, said end portions having out-turned parts extending away from each other and a yoke member engaging said end portions and extending across said open end of the looped member, said end portions projecting into said last mentioned member, said out-turned parts being constructed and arranged to releasably prevent withdrawal of said end portions from said last mentioned member, said yoke member having an opening through which all of said looped member except one of said out-turned parts is movable in either of two directions for assembling and disassembling said members, said one out-turned part being dimensioned in relation to said opening so as to limit movement of said looped member in one direction through said opening.

13. A device of the class described comprising a looped member open at one end thereof and terminating in end portions which are inclined

toward each other and a yoke member in which said end portions are received, said yoke member forming with said looped member a peripherally continuous structure defining an opening therein, said yoke member having laterally spaced side portions between which said end portions of said looped member are removably received, said yoke member having end portions connecting said side portions and directly engaged by said end portions, respectively, of said looped member, both of said end portions of said looped member being releasable from said yoke member and one of said end portions of said looped member having a pivotal engagement with the adjacent end of said yoke member between said side portions thereof about an axis extending between said side portions, said one of the end portions of said looped member having a transverse projection extending in the direction between said side portions of the yoke member and engaging the adjacent end of said yoke member to limit movement of said end of the yoke toward the end of said one of the end portions of the looped member, said other end portion of the looped member when engaged with said yoke member releasably preventing said pivotal movement of said looped member.

IRVING STEINHARDT.
